S. J. Mank

UNITED STATES PATENT OFFICE

JAMES ORENITS, OF ELMHURST, NEW YORK

LOUD SPEAKER

Application filed November 27, 1931. Serial No. 577,598.

This invention relates to loud speaker apparatus, such for example as that used in combination with radio receiving sets.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therefrom as do not affect the spirit of the invention nor exceed the scope thereof as expressed in the appended claims.

In the drawing:

Fig. 1 is an elevational view of the apparatus of my invention; and

Fig. 2 is a horizontal section taken approximately on the line 2—2 of Fig. 1, looking in the direction of the arrows.

Referring to the drawing for a more detailed description thereof, the numeral 3 indicates a base on which is mounted, in elevated position, by means of supports 4, a magnet 5. The mentioned magnet may be either a permanent magnet or an electromagnet and has confronting poles 6 and 7 spaced from each other. A soft iron bar 8 is secured to the mentioned magnet by means of non-magnetizable brackets 9, the bar 8 being spaced from the magnet 5 and being opposite the poles 6 and 7 of the same. An electrically conducting elongate loop 10 is positioned between the poles of the magnet and the bar 8 and is supported on conducting members 12, which are connected to the terminals of the secondary circuit 13 of a transformer 14, the terminals of the primary coil being connected to a microphone, for example. One side of the loop 10 is connected to a loud speaker 17 by means of a pin 18. The loud speaker 17 is mounted on a bracket 18' which is secured to the base 3. The elongate loop 10, I have found, has a greater amplitude of vibration than the usual circular loops employed and the apparatus described has been found by ex-

periment to give improved results over the previous types of loud speakers.

What is claimed as new and useful is:

1. A loud speaker apparatus comprising a magnet having oppositely disposed closely arranged poles, a bar of soft iron arranged in spanning relation to the poles but separated therefrom by an intervening space, a looped conductor disposed between said bar and said poles and arranged for connection to an energizing source and supported solely at one end to permit its being vibrated by variations in the current flowing therethrough, a diaphragm, and a drive pin connecting the diaphragm with said looped conductor. 55 60 65

2. A loud speaker apparatus comprising a magnet having oppositely disposed closely arranged poles, a bar of soft iron arranged in spanning relation to the poles but separated therefrom by an intervening space, a looped conductor disposed between said bar and said poles and arranged for connection to an energizing source and supported solely at one end to permit its being vibrated by variations in the current flowing therethrough, a diaphragm, and a drive pin connecting the diaphragm with said looped conductor at an intermediate point 70 75 80

In testimony whereof I hereby affix my signature.

JAMES ORENITS.
